UNITED STATES PATENT OFFICE.

GEORGE H. BURRILL, OF ADAVILLE, IOWA.

GRAIN-DRILL.

SPECIFICATION forming part of Letters Patent No. 709,741, dated September 23, 1902.

Application filed June 18, 1902. Serial No. 112,190. (No model.)

To all whom it may concern:

Be it known that I, GEORGE H. BURRILL, a citizen of the United States, residing at Adaville, in the county of Plymouth and State of Iowa, have invented a new and useful Grain-Drill, of which the following is a specification.

This invention relates generally to grain-drills, and more particularly to an improved 10 means for supporting the colter in advance of the shoe arranged adjacent to the drill-tube, the object of the invention being to provide a simple device by means of which the colter is pressed down upon the face of the 15 earth and will act independent of the drill-tube and shoe in its downward movement.

Another object is to provide a construction whereby as the drill-tube and shoe are elevated the colter will also be lifted from 20 the ground.

With these various objects in view the invention consists in the novel features of construction, combination, and arrangement, all of which will be fully described hereinafter 25 and pointed out in the claims.

In the drawings forming part of this specification, Figure 1 is a perspective view showing the practical application of my invention. Fig. 2 is a plan view of the same, the drill- 30 tube and shoe being omitted. Fig. 3 is a detail sectional view, partly in elevation. Fig. 4 is a detail perspective view of the spring-rod for pressing the colter to the ground.

Referring to the drawings, A indicates a 35 drill-tube, which is constructed and arranged substantially the same as drill-tubes now in use, the lower end of said tube being arranged between the parallel supporting-beams B, which beams are pivotally connected at their 40 forward ends to a rod C, forming a part of the drill-frame.

D indicates the ordinary shoe, which is arranged at the lower end of the drill-tube and in advance of the same, the forward end of 45 said shoe being arranged between and connected to the beams B.

The colter E is arranged between the beams B and in advance of the shoe D, said colter being circular in form and provided with a 50 double cutting edge E', which serves to break the earth and cut through any weeds or other

obstructions which might come in contact with the shoe. The colter E has an axle F rigidly connected therewith, said axle extending a short distance from each side or face 55 of the colter. The ends of the axle are journaled in the forked end of a bar G, the forward end of said bar being pivotally connected to the bar C between the beams B. A spring-rod H is arranged adjacent to the bar 60 G, the rear end being hooked, as shown at H', and adapted to engage the said bar adjacent to its bifurcation. The rod H is passed under the bar C, then around the said bar, as shown at H², and is provided with a trans- 65 verse portion H³, which is arranged beneath the beams B, thereby exerting a downward pressure upon the ends H', thus serving to press the colter down into the ground. It is obvious from this construction that the 70 colter will be normally held in contact with the ground, but will be permitted to spring upwardly whenever any obstacle is encountered. The colter is held independent of the shoe and drill-tube and serves to cut the 75 ground, weeds, and the like prior to the contact of the shoe. Whenever the drill-tube and shoe are lifted, the beams B are of course elevated, and the said beams engaging the axle of the colter serve to elevate the said 80 colter simultaneous with the elevation of the tube and shoe.

A' indicates the usual construction of spring and bar employed for holding the tube projected downwardly and also lifting the shoe, 85 and A² indicates the usual form of drag-chain for covering the grain.

Having thus fully described my invention, what I claim as new, and desire to secure by Letters Patent, is—

1. The combination with the drill-tube, shoe and supporting-beams, of the colter arranged between the beams, the bifurcated bar carrying the colter, and a spring adapted to bear upon the said bar for the purpose of holding 95 the colter in contact with the earth, as specified.

2. The combination with the drill-tube, shoe and beams, of a colter arranged between the beams, bifurcated bar carrying the colter, and the spring-rod, one end of which engages the said bar adjacent to its bifurcation, the

other end engaging the beams, said spring-rod normally holding the colter in contact with the earth, substantially as specified.

3. The combination with the drill-tube, shoe and beams, of the colter arranged between the beams and having its axle adapted to engage the said beams, a bar bifurcated at one end and carrying a colter within said bifurcated end, and a spring-rod hooked at one

end and adapted to engage the said bifurcated bar adjacent to its bifurcation, the opposite end being hooked or bent when brought into engagement with the under side of the beams for the purpose specified.

GEORGE H. BURRILL.
